UNITED STATES PATENT OFFICE

JOHN H. KOEBERLE, OF WILLOW GROVE, PENNSYLVANIA, ASSIGNOR TO MAX
A. MARSCHNER, OF WILLOW GROVE, PENNSYLVANIA

AUTOMATIC SAFETY STOP ATTACHMENT FOR KNITTING MACHINES

Application filed July 18, 1931. Serial No. 551,593.

My invention relates to a new and useful automatic safety stop attachment for knitting machines and more particularly to the type of knitting machines known as loopers, 5 of the general type disclosed in United States patent to Wright 1,092,885, issued April 14th, 1914, and United States patents to Davis 1,050,432 and 1,050,433, both issued January 14th, 1913, and the patent to Davis 1,054,658, 10 issued February 25th, 1913.

My invention further relates to an automatic safety stop attachment which is adapted to stop a looping machine automatically when any waste material is caught in the pin cylinder of the looping machine, to prevent 15 breaking of the looping needle or any interference with the uniform regular operation of the looping needle. My safety stop attachment is also adapted to stop the looping machine automatically immediately upon the missing of a stitch by the looping needle, thereby preventing the formation of defective products which are sold at a lower price as "seconds".

25 My invention further relates to a safety stop attachment of the general character set forth, which is electrically operated and which is so connected to the starting and stopping mechanism of the looping machine so as to be effective at all times during the running of the looping machine.

My invention further relates to an automatic safety stop attachment of this general character which can be applied to machines 30 already manufactured without in any way interfering with their structure or assembly and one which can be made and assembled at nominal cost.

With the above ends in view, my invention 35 consists in providing an electromagnet positioned above the yarn guide which feeds the yarn or thread to the pin cylinder of the looping machine, said electromagnet being adapted to be energized by the closing of a normally open switch positioned above and in close proximity to the pin cylinder in advance of the looping needle, said switch being adapted to be closed by the existence of any obstruction carried by or resting upon 40 the pin cylinder.

My invention further consists in positioning a second normally open switch immediately above the yarn guide which guides the yarn before the latter is knit by the looping needle, said switch being adapted to be 55 closed by the slackening of the yarn passing through said yarn guide, due to the missing of a stitch by the looping needle.

My invention further consists in so positioning the electromagnet referred to, so as 60 to cause the dropping of the trip arm or lever which normally rides or rests on the yarn being knit when said electromagnet is energized, from the normal position of said trip lever upon the yarn, thereby effecting the 65 stopping of the looping machine in the conventional manner in which such machine would be stopped, if the yarn on which said trip lever usually rides were to break, according to the construction disclosed in the 70 patents referred to and which will hereinafter be generally set forth.

My invention further consists in various other novel features of construction advantage, all as hereinafter described and claimed 75 in connection with the accompanying drawings, in which:

Figure 1 represents a fragmentary, dia- 80 grammatic plan view of a conventional looping machine provided with a safety stop attachment embodying my invention.

Figure 2 represents a diagrammatic view 85 and side elevation showing the general allocation and arrangement of the pertinent co-acting parts.

Figure 3 is a view similar to Figure 2 showing the paths of the yarn in relation to certain of the coacting parts shown in Figure 2.

Figure 4 represents a fragmentary, dia- 90 grammatic view and side elevation showing the means of starting and stopping the machine in relation to the automatic safety stop construction forming the subject of my invention.

Figures 5 to 9, inclusive, show details of 95 the switches adapted to actuate my novel safety stop attachment.

Figure 10 represents a diagrammatic view 100 showing the general plan of the conventional starting and stopping mechanism in its rela-

tion to the safety stop attachment of my invention.

Referring to the drawings, in which like reference characters indicate like parts, 20 5 designates the bed plate or support of a conventional looping machine, from which extends the horizontal supporting arm 22 which supports the disc or dial plate 24, around which is adapted to revolve in a uniform continuous manner pin cylinder 26, which is driven by suitable connections (not shown) from the shaft 28. The shaft 28 carries and is driven by the cone clutch 30 which is adapted to engage a corresponding seat in 15 the pulley 32 which is driven by the belt 34. The cone clutch 30 is engaged or disengaged by moving the push rod 35 which is pivoted at 37 to the link 38 which is pivoted at 39. When the push rod 35 is pulled in the direction 20 of the arrow 36 the cone clutch 30 is engaged and the shaft 28 revolves to drive the looping machine. When it is desired to stop the machine, the push rod 35 is pushed in the opposite direction to disengage the cone 25 clutch 30.

Heretofore looping machines of this general character have been provided with a mechanically operated automatic safety stop attachment which consisted of a trip lever 30 40 which normally rides on the yarn 42 and which, when the yarn 42 breaks, is adapted to drop, thus causing the arm 46, to which the trip lever is rigidly secured, to turn on its axis to lower the crank portion 50 of the 35 arm 46, on which rests the finger 52 of the arm 54, thus causing the arm 54, to which the finger 52 is rigidly secured, to turn upon its axis, so as to bring the hooked end 56 of the arm 54 into the path of the pin or lug 40 58 on the wheel 60 on the shaft 28. The engagement of the pin 58 with the hooked end 56 of the arm 54 draws the arm 54 in the direction of the arrow (Fig. 10) thereby causing the finger 52 to engage the finger 64 45 which is rigidly secured at 66 to the starting and stopping push rod or lever 35, to move the latter in a direction opposite to the direction of the arrow 36 to disengage the clutch 30, thereby stopping the machine. The construction heretofore described constitutes the 50 only safety stop arrangement provided on looping machines of the character referred to and disclosed in the prior patents above mentioned and serves to stop the machine 55 only when and if the yarn 42 breaks.

In order to utilize this same stopping mechanism to stop the machine when the pin cylinder is obstructed or when, during the looping operation a stitch is missed, I provide the 60 electromagnet 70, which, when energized, is adapted to draw up the upper yarn guide 72 thereby laterally to displace the yarn 42 from under the trip lever 40, thus causing the trip lever 40 to drop and hence to stop the machine in the manner heretofore described

in connection with the breaking of the yarn 42. The yarn guide 72 is tapered upwardly as best shown in Figure 10 and while the yarn 42 bears on the upper thin end of the guide 72 it remains under the tip of the trip lever 40. When the yarn guide 72 is raised by action of the magnet 70 the yarn 42 bears against the lower thicket portion of the yarn guide 72 and is in that way laterally displaced from under the trip lever 40 thus causing the latter to fall. The electromagnet 70 is adapted to be energized by the transformer 74 into which electrical energy is delivered by the wires 76 leading from any desirable source of electrical current. From the transformer 74 extends the wire 78 which is secured to the binding post 80, from which extends the wire 81 to the binding post 82 of the normally open spring switch 84, said spring switch 84 being closed to "ground" the circuit only when the starting and stopping push rod 35 is in its forward position, that is, when the machine is in operation, in which position the push rod 35 the cam 85 on said push rod is in contact with said switch. (See Figures 90 4 and 10.) Another wire 86 leads from the transformer 74 to the binding post 88, from which a wire 89 leads to the binding post 90, from which a wire 92 extends to one end of the coil of the electromagnet 70. From the other end of the coil of the electromagnet 70 another wire 98 extends to the binding post 100, from which two wires 102 and 104 extend to the binding posts 106 and 108 of the normally open switches 110 and 112 respectively. 100

With the switch 84 closed during the running of the machine, the electromagnet 70 will only be energized when one or both of the switches 110 and 112 are closed to complete the circuit through the electromagnet. 105 Thus if a piece of waste or other obstruction 114 is caught in the pin cylinder 26, it must pass under the spring contact member 116, which is connected to the electric circuit by the wire 112a, thereby pushing the latter upwardly against the binding post 108 of the switch 112, thereby closing the circuit and energizing the electromagnet 70, whereupon the arm 72 is attracted upwardly towards the magnet thus withdrawing the yarn 42 from under the trip lever 40 and causing the latter to drop, thereby to stop the machine in the manner heretofore described in exactly the same way as if the yarn 42 had broken. In this way, the machine is stopped before the waste or other obstruction 114 reaches the looping needle 118 (see Figure 2) to prevent the breaking of said needle or the improper operation thereof. Similarly, when the yarn 42 becomes slack, due to the missing of one or more stitches by the looping needle 118, the resilient yarn guide 121, through which the yarn 42 must pass prior to reaching the looping needle, and which is normally prevented from closing the switch 110 by the ten- 110 115 120 125 130

sion of the yarn 42, moves upwardly, due to its own springy character, against the contact member 120 thereby to close the switch 110 and to complete the electric circuit with 5 which it is connected by the wire 121 α through the electromagnet 70 again to energize the latter and to pull the arm 72 upwardly thereby to withdraw the yarn 42 from under the trip lever 40, thus causing the machine to stop in the manner heretofore set forth.

I have deemed it unnecessary in the present specification to illustrate the looping machine completely or to describe in detail the 15 operation of the looping machine, since these machines are fully disclosed in the patents referred to in the preamble, and since they are extensively sold by the Southern Textile Machinery Company, of Paducah, Kentucky, 20 and are of familiar structure and operation to anyone engaged in the manufacture of hosiery or other knit products. My invention consists only in providing the two switches 110 and 112, which are adapted to be closed 25 by the slackening of the yarn 42, due to the missing of a stitch or by an obstruction 114 in the pin cylinder 26, to complete an electric circuit leading to the electromagnet 70 to energize the latter to draw up the yarn guide 72 30 to withdraw the yarn 42 from under the trip lever 40, which trip lever forms part of the conventional looping machine and acts to stop the machine in a mechanical manner, which is herein described and which forms part of 35 the looping machines as sold by the Southern Textile Machinery Company referred to.

While I have described my invention as operating to stop the looping machine automatically when the yarn becomes slack or 40 when the pin cylinder becomes obstructed it is obvious that my invention is equally applicable, with or without slight changes or allocation of parts to operate to stop the looping machine when other defects arise, such as the 45 loosening of the looping needle to undue projection, or to twisting of a pin on the pin cylinder, etc., and that my attachment does not interfere with the normal operation of the stopping attachment provided for stopping 50 the machine when the yarn breaks.

Having thus described my invention, what I claim as new and desire to secure by Letters Patent is:

1. The combination with a looping machine, including a pin cylinder, a driving mechanism, and a pin cylinder stopping mechanism, of a contact member forming part of a normally open switch and positioned near said pin cylinder, said contact 55 member being adapted to close said switch by an obstruction in said pin cylinder, an electric circuit connected to said switch, a trip lever normally riding on the yarn used in said looping machine and adapted, when 60 dropping off said yarn, to operate said stop-

ping mechanism, an electro-magnet adapted to be energized by the completion of said electric circuit upon the closure of said switch by said contact member, and a guide adapted to be actuated by said electro-magnet to dis- 76 place said yarn from under said trip lever.

2. The combination with a looping machine, including a pin cylinder, a driving mechanism, and a pin cylinder stopping mechanism, of a resilient yarn guide forming 75 part of a normally open switch, a yarn passing through said yarn guide and normally tensioning the latter to maintain said switch in open condition, a trip lever normally riding on said yarn and adapted, when falling off said yarn by the slackening, breaking or displacement of said yarn, to actuate said stopping mechanism, an electric circuit connected to said switch, an auxiliary guide adapted, when actuated, to displace said yarn 80 from under said trip lever, and an electro-magnet connected to said circuit and adapted, when energized, to actuate said auxiliary 85 guide.

In testimony whereof I affix my signature. 90

JOHN H. KOEBERLE.
